(57) **CLAIM**

The ornamental design for a container application surface, as shown and described.

DESCRIPTION

FIG. 1 is a top view of a container application surface, embodying our new design;

FIG. 2 is a perspective view thereof;

FIG. 3 is a left side elevational view; the right side being identical; and,

FIG. 4 is front elevational view, the rear elevational view being identical.

The broken lines in the Figures are for illustrative purposes only and form no part of the claimed design.
